Fig. 7.

Fig. 8.

Fig. 9.

Fig. 10.

Fig. 11.

FIG. 12.

FIG. 13.

FIG. 1 is a perspective view of a carton toy showing my new design, wherein the driver or front portion of the vehicle is located on the flat end thereof;

FIG. 2 is an end elevational view thereof;

FIG. 3 is a side elevational view thereof showing the side opposite that appearing in FIG. 1;

FIG. 4 is an elevational view of the end thereof opposite that shown in FIG. 2;

FIG. 5 is a top plan view thereof;

FIG. 6 is a bottom plan view thereof;

FIG. 7 is a perspective view of the carton toy wherein the driver or front end of the vehicle is located on the peaked end thereof;

FIG. 8 is an end elevational view of the toy of FIG. 7;

FIG. 9 is a side elevational view thereof;

FIG. 10 is a bottom plan view thereof of FIG. 7;

FIG. 11 is an end elevational view thereof showing the end opposite that appearing in FIG. 8;

FIG. 12 is a top plan view thereof;

FIG. 13 is an elevational view of the side opposite that appearing in FIG. 9.

I claim:

The ornamental design for a carton toy, as shown and described.
